UNITED STATES PATENT OFFICE

125,238

DESIGN FOR PAPER FOR COVERING AND PROTECTING ARTICLES OF SALE

Max Kirchheimer, Chicago, Ill., assignor to Kirchheimer Brothers Co., Chicago, Ill., a corporation
of Illinois

Application October 8, 1940, Serial No. 95,685

Term of patent 14 years

To all whom it may concern:

Be it known that I, Max Kirchheimer, a citizen of the United States, residing at Chicago, in the county of Cook and State of Illinois, have invented a new, original, and ornamental Design for Paper for Covering and Protecting Articles of Sale, of which the following is a specification,
reference being had to the accompanying drawing, forming a part thereof.

In the drawing:

The single figure shows a fragmentary face
view of a piece of paper for covering and protecting articles of sale with my design illustrated thereon.

I claim:

The ornamental design for paper for covering
and protecting articles of sale, as shown.
